RAYMOND C. McALLISTER, OF PAINTED POST, NEW YORK, ASSIGNOR TO INGERSOLL-RAND COMPANY, OF JERSEY CITY, NEW JERSEY, A CORPORATION OF NEW JERSEY

CONNECTER

Application filed May 6, 1932. Serial No. 609,753.

This invention relates to connecters, but more particularly to a connecter to be interposed between a driving rod and a driven rod adapted to work in substantially coaxial relationship. In multi-stage compressors it is sometimes convenient to arrange the separate stages thereof in tandem with an extension of the piston in one stage acting as the piston in a higher stage. It is commonly arranged that the piston in the higher stage is upon its compression stroke at the time that the piston of the lower stage is upon the intake stroke and vice versa, thereby placing a more constant load upon the driving member. In practice, however, it sometimes becomes very expensive to align the compression cylinders with the meticulous accuracy necessary when the extension of one piston itself acts as a piston in another cylinder. The accuracy requirements are not impracticably close in compressors of comparatively low pressure, for in such cases working tolerances may be relatively great and the clearance made up by packing, piston rings, or by similar leakage prevention devices. In compressors, however, in which the final stage is adapted to compress air or other gases to an extremely high pressure, as to 10,000 or 15,000 pounds per square inch, piston rings and other packing devices are inadequate to withstand such pressures unless the tolerances between metal surfaces are extremely minute and it is commercially impracticable to align cylinders with the extreme accuracy necessitated by such minute tolerances.

It is an object of this invention to provide a connecting means between the piston of the lower stage cylinder and the piston of the higher stage cylinder of a type which will permit an appreciable disalignment between the cylinders but will transmit the thrust of one piston to the other so that although separate pistons are employed and they are slightly out of coaxial alignment, nevertheless they are for all practical mechanical purposes a single piston and extension.

Other objects are either apparent or will be pointed out hereinafter.

In the accompanying drawing, Figure 1 is a longitudinal section through

a connecting box between compressor stages which encloses the connecter which is the subject of the present invention.

Figure 2 is an outside view of the connecter housing, 55

Figure 3 is a perspective view of the double socket joint employed in the connecter, and

Figure 4 is a sectional view of the connecter in which the connected members are shown out of alignment. 60

A cylinder casing 5 of a low pressure cylinder is connected to a cylinder casing 7 of a high pressure cylinder by a connecting box 9. An extension 11 of the low pressure cylinder piston extends through suitable packing 65 13 of the low pressure cylinder into the connecting box 9. A piston 15 from the high pressure cylinder 7 extends through a rear cylinder closure 17 into the connecting box 9.

Upon a threaded end 19 of the piston extension 11 is a nut 21. Also threaded on the end 19 is a connecter housing 23 which is provided with a hexagonal head 25 for convenience in assembly. The hexagonal head 25 and the nut 21 are adapted to be forced together in pressure locking engagement. The connecter housing 23 is preferably cylindrical or barrel-shaped and has a hollow center into which extends a rounded tip 27 of the rod 11. Abutting the rounded tip 27 is a 80 double-ended socket 29 in the form of a spool which may have an annular groove 31 in the middle and having at each end concavities 33.

One of the concavities 33 is adapted to engage the convex tip 27 of the extension 11. The concavities 33 are preferably of the same radius as the rounded tip 27 to permit easy movement of the socket upon the tip. 85

The base of the piston 15 extends into the connecter 23 through a bore 35 in which it is freely movable. The end of the piston is provided with a button 37 which has a rounded face in contact with the opposite concavity 33 of the spool 29, which is thus interposed 90 between the ends of the extension 11 and the piston 15. The advisability of having the rounded head 37 of the same radius as the concavity 33 will be apparent.

Interposed between the button 37 of the 100

piston 15 and the end of the connector 23 through which the piston 15 extends is a spring 39 which is preferably maintained at sufficient tension to maintain the button 37 of the piston 15 in constant engagement with a concavity 33 of the spool 29 when the piston 15 is on its suction stroke. It will be obvious that the tension on this spring can be readily adjusted by regulating the distance 10 by which the head 27 of the piston extension 11 projects into the connector housing 23.

In order to introduce grease for lubricating purposes a hole 41 is provided through the housing 23.

15 In operation the spool 29 acts as a double socket for a double ball and socket joint in which the spool 29 is the socket and the rounded ends 27 and 37 are the balls. In this way the thrust of the piston extension 26 11 may be transmitted directly to the piston 15 through an appreciable angular displacement by means of the spool 29. It will be clear that this angular displacement will vary according to the position of the piston 15, 25 the angle being greater when the piston has reached the end of its compression stroke and less when the piston has reached the end of its intake stroke. Thus it will be seen that the spool 29 is constantly oscillating through 30 a small arc during the operation of the compressor and the piston 15 is similarly changing its position with respect to the opening 35 in the casing 23. A reference to Figure 4 will illustrate this condition.

35 Having thus described this invention, I claim:

1. A connector comprising a casing adapted to be attached to a driving member and having a bore therethrough, a driven member 40 extending into the bore, means in the bore movable with respect to the driving member and the driven member and seating against the adjacent ends of the members, and means 45 acting upon the driven member to hold the driven member in contact with said movable means.

2. A connector comprising a casing adapted to be attached to a driving member and having a bore therethrough, a driven member 50 extending into the bore, means in the bore movable with respect to the driving member and the driven member and interposed therebetween, and means acting upon the casing and the driven member to hold the driven 55 member in contact with said movable means.

3. A connector comprising a casing adapted to be attached to a driving member and having a bore therethrough, a driven member extending into the bore, means in the bore 60 movable with respect to the driving member and the driven member and interposed therebetween, and means in the casing acting upon the casing and the driven member to hold the driven member against axial movement 65 with respect to the casing.

4. A connector comprising a casing adapted to be attached to a driving member and having a bore therethrough, a driven member extending into the bore, convex ends on the driving member and the driven member, an intermediate member having concave sockets in engagement with the convex ends of the driving and driven members, and means to hold the driven member against axial movement with respect to the casing. 70 75

5. A connector comprising a casing adapted to be attached to a driving member and having a bore therethrough, a driven member extending into the bore, convex ends on the driving member and the driven member, an intermediate member having concave sockets in engagement with the convex ends of the driving and driven members, and a spring 80 acting upon the driven member and upon the casing to hold them against relative axial 85 movement. 80

6. A connector comprising a casing, a driving member affixed thereto and having a spherical end surface, a driven member extending loosely into the casing and having a spherical surface, means interposed between the members and having spherical end surfaces to seat against the spherical surfaces on the driving and driven members, and means acting against the driven member to hold the spherical surfaces in contact with each other. 90 95

In testimony whereof I have signed this specification.
